[57] CLAIM

The ornamental design for a ceiling fan, as shown and described.

DESCRIPTION

FIG. 1 is a side, bottom perspective view of a ceiling fan showing my new design;

FIG. 2 is a cross-sectional view thereof, on a reduced scale, taken along the line 2—2 in FIG. 4 and looking in the direction of the arrows;

FIG. 3 is a bottom plan view thereof on a reduced scale; and,

FIG. 4 is a side elevational view thereof, the remaining side views being substantially the same.

Fig.2
